UNITED STATES PATENT OFFICE.

LUIGI D'AURIA, OF PHILADELPHIA, PENNSYLVANIA.

NON-ROTATIVE PUMPING-ENGINE.

SPECIFICATION forming part of Letters Patent No. 718,808, dated January 20, 1903.

Application filed May 8, 1901. Serial No. 59,269. (No model.)

To all whom it may concern:

Be it known that I, LUIGI D'AURIA, a subject of the King of Italy, (having resided in the United States during the past twenty-five 5 years and having declared my intention of becoming a citizen of the United States,) residing in Philadelphia, Pennsylvania, have invented certain Improvements in Non-Rota-
tive Pumping-Engines, of which the following is a specification.

My invention consists of certain improvements in the hydraulic compensator for non-rotative pumping-engines heretofore invented by me, one example of such hydraulic compensator being shown in my Patent No. 493,153, dated March 7, 1893, and another being shown in my application for patent filed July 21, 1899, Serial No. 724,665.

The object of my present invention is to furnish means whereby non-rotative pumping-engines provided with my hydraulic compensator may be permitted to change their speed and therefore their pumping capacity within wide limits without necessarily changing the 25 grade of steam expansion or the pressures upon the engine and pump, and therefore without affecting the steam economy. This object I attain in the manner hereinafter set forth, reference being had to the accompanying drawing, which represents in side elevation a non-rotative pumping-engine of the type shown in my application for patent, Serial No. 724,665, before referred to, with my present improvement in the compensator applied thereto.

In the drawing, 1 represents the high-pressure steam-cylinder of the pump; 2, the low-pressure steam-cylinder of the same; 3, the pump-cylinder; 4, the compensating cylinder; 5, the rod carrying the steam-cylinder pistons, compensating-cylinder plunger, and pump-plunger, and 6 the flow-pipe communicating with the opposite ends of the compensating cylinder.

The action of the compensator is fully set forth in my former patent, and hence it will not be necessary to describe the same in this specification further than to say that the back-and-forth flow of the liquid through the 50 flow-pipe 6 under the action of the reciprocating plunger in the compensator-cylinder has the effect of equalizing the operation of

the pump when the steam is employed expansively and renders unnecessary the use of any fly-wheel or other balancing agent. 55

I have ascertained that a by-pass extending from the chamber of the hydraulic compensator on one side of the plunger to the chamber on the opposite side of said plunger will have the effect of increasing the piston 60 speed of the pump and that this increase of speed is in accordance with the following law: Let A represent the area of the compensator-plunger, L the length of the reciprocating liquid column, A' the area of the by-pass 65 when fully open, and L' the length of said by-pass. Then with the by-pass shut the piston speed under fixed conditions of steam expansion will be a minimum and proportional to the square root of the ratio A divided by 70 L, and with the by-pass fully open the piston speed will be a maximum and proportional to the square root of the sum of the ratios A divided by L and A' divided by L'. With the addition of other by-passes whose 75 full areas and length are represented, respectively, by $A^2 L^2$, $A^3 L^3$, &c., the maximum piston speed with all by-passes open will be proportional to the square root of the sum of the ratios A divided by L, $A' 80$ divided by L' , A^2 divided by L^2 , A^3 divided by L^3 , &c.

The above law does not take friction into consideration, but is sufficient in practice to determine the proper dimensions of the by- 85 pass or by-passes to obtain a given maximum piston speed when the minimum is given.

To obtain the object of my invention I proportion the area of the plunger and the reciprocating liquid column of the hydraulic 90 compensator, so that with a grade of steam expansion corresponding to the best steam economy of the engine the piston speed shall be a given minimum, and I connect the chamber of the hydraulic compensator on one side 95 of the plunger with the chamber on the other side of said plunger by means of a valved by-pass of such size that when fully open it will cause an increase of piston speed corresponding to the desired maximum, any intermediate speed being secured by a proper adjustment of the by-pass valve, so as to vary the effective area of said by-pass without changing the point of cut-off of the steam or the

grade of steam expansion of the engine. It is obvious that the by-pass should be so proportioned as to length and internal area that when its valve is fully opened the column 5 of water in said by-pass shall have the same oscillatory period as that of the column in the main compensator-pipe. In the drawing the by-pass is shown at 7 and its valve at 9. The valve is preferably of the balanced type and 10 operated automatically by a pressure device communicating with the pump, so that the valve will be opened or closed in accordance with decrease or increase of pressure in the delivery-chamber of the pump in order to 15 maintain a substantially uniform pressure of delivery by varying the speed of the engine to accord with the demands upon the pump.

Any ordinary form of diaphragm or piston regulator may be employed, the casing of one 20 such form of regulator being shown at 10 in communication with the air-chamber 11 of the pump and the stem of this regulator acting upon a lever 12, which is connected by a rod 13 to the stem of the valve 9, a pull- 25 spring 14 acting upon the lever 12 in opposition to the action of the pressure device thereupon. When the pump delivers into a stand-pipe or reservoir in which a constant level is to be maintained, a float may take the 30 place of the pressure device, said float acting

so as to close the valve 9 when the desired level has been attained and to open said valve when the level falls.

Having thus described my invention, I claim and desire to secure by Letters Pat- 35 ent—

1. The combination of the compensator-cylinder of a non-rotative pumping-engine, with a by-pass connecting the opposite ends of said compensator-cylinder and a valve in said 40 by-pass whereby the area of the passage through the by-pass may be regulated according to the demands upon the pump, substantially as specified.

2. The combination of the compensator-cylinder of a non-rotative pumping-engine, with a valved by-pass connecting the chamber on one side of the compensator-plunger with the chamber on the other side of the same, and means for automatically operating said by- 45 pass valve to increase or decrease the speed of the engine in accordance with the demand upon the pump, substantially as specified.

In testimony whereof I have signed my name to this specification in the presence of 55 two subscribing witnesses.

LUIGI D'AURIA.
